UNITED STATES PATENT OFFICE.

PAUL ARTHUR, OF DETROIT, MICHIGAN.

DESIGN FOR AN AUTOMOBILE RADIATOR.

No. 38,962.

Specification for Design.

Patented Dec. 24, 1907.

Application filed February 11, 1907. Serial No. 356,935. Term of patent 3½ years.

To all whom it may concern:

Be it known that I, PAUL ARTHUR, a citizen of the United States, residing at Detroit, in the county of Wayne and State of Michigan, have invented a new, original, and ornamental Design for Automobile-Radiators, of which the following is a specification, reference being had to the accompanying drawing, forming part thereof.

The figure is an end elevation of automobile radiator, showing my new design.

I claim:

The ornamental design for automobile radiator, as shown.

PAUL ARTHUR.
